UNITED STATES PATENT OFFICE.

WILLIAM LOUIS WINANS, OF LONDON, ENGLAND, AND THOMAS WINANS,
OF BALTIMORE, MARYLAND.

IMPROVED APPLICATION OF RUDDERS TO SPINDLE-SHAPED HULLS.

Specification forming part of Letters Patent No. 58,743, dated October 9, 1866.

To all whom it may concern:

Be it known that we, WILLIAM LOUIS WINANS, of London, England, and THOMAS WINANS, of Baltimore, United States of America, have invented Improvements in Adapting Screw-Propellers for Propelling Ships or Vessels for Ocean Navigation; and we do hereby declare that the following is a full and exact description of our said invention.

Our present invention of improvements relates to adapting rudders to a spindle-shaped hull, such as was invented by Ross and Thomas Winans and for which Letters Patent were granted to them 26th October, 1858, No. 21,917.

This invention consists in the arrangement of the rudder as applied to propellers of spindle-shaped hulls.

The propeller shaft or shafts may be placed in any suitable position in the vessel, at or below the center line or line of flotation, and may be actuated by the same or by separate engines, and the propellers may be driven in the same or in opposite directions.

The invention likewise consists in similar adaptations and combinations of propellers to or with a spindle-shaped hull having a flat, or nearly flat, upper deck with bulwarks, railing, or cabin or cabins, with upper or hurricane deck, similar to that invented by us, and for which we have applied for Letters Patent.

In the accompanying drawings, Figure 1, Sheet I, is a side elevation of part of a spindle-shaped vessel, with a screw-propeller, *a*, adapted near to one end. Fig. 2 is a front view of the same.

The propeller may be of the ordinary construction, and is mounted on one end of the shaft *b*, which may be, if desired, provided at the other end with a similar propeller. The projecting end of the shaft *b* is supported in bearings in the brackets *c c*, which are secured to the pointed end of the vessel.

The rudder *d d* is placed in front of the propeller, and is made double—that is, there are

two plates, one on each side of the propeller-shaft.

Fig. 3 is a side elevation of part of a spindle-shaped vessel, to which two propellers are adapted at the same end of the vessel. Fig. 4 is a front view of this part.

It will of course be obvious that in combination with these two propellers one or two propellers may be adapted to the opposite end of the vessel, so that the vessel may have two, three, or four propellers.

When there are two propellers at the same end of the vessel the rudder which is placed in advance is situated between the two propelling-shafts, which are supported by bracket-arms, as in the former instance.

Having now described our invention of improvements in adapting screw-propellers for propelling ships or vessels for ocean navigation, and having explained a manner of carrying the same into effect, we claim as our invention—

1. The rudders *d*, placed between the brackets *c* and the midship of the spindle-shaped hull, its leaves occupying respective sides of the single propeller-shaft, substantially as described, for the purpose specified.

2. The central rudder, *d*, placed between the brackets *c* and the midship of the spindle-shaped hull, when arranged with more than one propeller-shaft, substantially as described, for the purpose specified.

In witness whereof we, the said WILLIAM LOUIS WINANS and THOMAS WINANS, have hereunto set our hands and seals the 20th day of January, 1866.

WM. L. WINANS. [L. S.]
THOMAS WINANS. [L. S.]
